CLAIM

The ornamental design for a toilet seat, as shown and described.

DESCRIPTION

FIG. 1 is a bottom plan view of a first embodiment of a toilet seat showing my new design,

FIG. 2 is a bottom perspective view thereof when partially opened,

FIG. 3 is a top perspective view thereof,

FIG. 4 is a right side perspective view thereof,

FIG. 5 is a left side perspective view thereof, and

FIG. 6 is a right side elevational view thereof, the left side elevational view being a mirror image,

FIG. 7 is a bottom plan view of a second embodiment of a toilet seat showing my new design,

FIG. 8 is a bottom perspective view thereof when partially opened,

FIG. 9 is a top perspective view thereof,

FIG. 10 is a right side perspective view thereof,

FIG. 11 is a left side perspective view thereof, and,

FIG. 12 is a right side elevational view thereof, the left side elevational view being a mirror image.
